UNITED STATES PATENT OFFICE.

GEORGE H. DOERING, OF BROOKLYN, NEW YORK.

TROLLING SPOON.

Application filed February 28, 1921. Serial No. 448,495.

To all whom it may concern:

Be it known that I, GEORGE H. DOERING, a citizen of the United States, and resident of the borough of Brooklyn, in the county of 5 Kings, city and State of New York, have invented certain new and useful Improvements in Trolling Spoons, of which the following is a specification.

This invention relates to improvements 10 in trolling spoons, and consists in certain novel features of construction hereinafter described and set forth in the claim whereby the utility, durability and attractiveness of the spoon is increased.

15 In the drawings:

Figure 1 is a plan view of the spoon; Fig. 2 a longitudinal sectional view thereof; and

20 Fig. 3 a central transverse sectional view thereof.

The main body portion 1 of the spoon consists of a single piece of mother of pearl of elliptical form in plan view and concavo-convex in both longitudinal and transverse 25 section. A pair of metal eyelets 2 extend through the body portion 1 of the spoon adjacent opposite ends of the spoon, the ends of the eyelets being headed against opposite faces of the spoon body. A strip of sheet 30 metal 3 of channel form extends entirely around the outer edge of the body portion 1, the edge of the body portion being confined in the channel of this metallic frame. The meeting ends of the metal strip are secured 35 together at 4 in overlapped relation preferably by soldering or spot welding the same to each other.

The usual gang hook 5 is attached to one 40 end of the spoon by a split ring 6, and one end of the usual swivel 7 is attached to the other end of the spoon by a split ring 8, said rings extending through the adjacent eyelets 2 and the usual eyes in the hook and swivel. The rings 6 and 8 are of the "key-ring" 45 type. The line, not shown, is adapted to be connected to the other end of swivel 7.

The mother of pearl body 1 forms a light and attractive spoon which is multi-colored and iridescent and not affected by moisture. 50 The endless metal strip 3 forms an edge binding for the mother of pearl body which protects and reinforces the frangible body

portion of the spoon. The contrast in color between the metal frame or binding and the spoon body also adds to the attractiveness of 55 the spoon.

An important feature of the invention resides in the fact that the metal binding strip forms an all metal link extending through both of the split rings, which link will maintain a connection between the hook and the line if the pearl spoon body should become fractured owing to strain or to a fish striking the spoon.

It will also be observed that the channel 65 frame will retain the parts of the frangible spoon body even after cracking or fracturing of the body, so that the utility of the spoon is not destroyed if the body 1 becomes cracked or fractured. A further advantage of the metal binding or frame consists in the fact that it prevents pulling out 70 of the eyelets through the ends of the spoon body. This frequently occurs in spoons heretofore used owing to splitting of the 75 narrow strips of the spoon body between the eyelets and the ends of the spoon. The metal binding will prevent spreading of split end portions of the spoon and thus prevent pulling the eyelets and split rings out 80 through the ends of the spoon.

It will be obvious that the spoon body 1 may be formed of other material than that specified.

What I claim is:

A trolling device comprising a spoon-body formed of a single piece of mother of pearl provided with two oppositely disposed apertures located a substantial distance from the outer edge of said body, metal edge-bindings for said apertures held to the spoon-body, a sheet metal frame extending entirely around the outer edge of the spoon-body outside of said metal-bound apertures and provided with an inwardly facing channel in 95 which the edge of the body is confined, a pair of rings each extending through one of said metal-bound apertures and encircling the adjacent portion of said sheet metal frame, a fish-hook attached to one ring, and a swivel 100 attached at one end to the other ring.

In testimony whereof I hereunto affix my signature.

GEORGE H. DOERING.
